RIDING-TYPE POWER LAWNMOWER

Viktor Schreckengost, Cleveland Heights, Ohio, assignor
to The Murray Ohio Manufacturing Co., Nashville,
Tenn., a corporation of Ohio

Filed Oct. 22, 1968, Ser. No. 14,118

Term of patent 14 years

Int. Cl. D8—01

U.S. Cl. D40—1

FIG. 5

FIG. 6

FIGURE 1 is a perspective view of a riding-type power lawnmower;

FIGURE 2 is a top plan view thereof;

FIGURE 3 is a perspective view of the side opposite that shown in FIGURE 1;

FIGURE 4 is a perspective view of the side opposite that illustrated in FIGURE 3;

FIGURE 5 is a perspective view taken from the front of the lawnmower; and

FIGURE 6 is a perspective view taken from the rear.

I claim:

The ornamental design for a riding-type power lawnmower, substantially as shown.
